UNITED STATES PATENT OFFICE.

RALPH F. CRAWFORD, OF SALINA, KANSAS.

INTERNAL-COMBUSTION ENGINE.

Application filed September 13, 1923. Serial No. 662,495.

To all whom it may concern:

Be it known that I, RALPH F. CRAWFORD, a citizen of the United States, residing at Salina, in the county of Saline and State of Kansas, have made a certain new and useful Invention in Internal-Combustion Engines, of which the following is a specification.

Figure 1 is a central longitudinal section through an internal combustion engine embodying the invention.

Figure 2 is a section taken on line 2—2, Figure 1.

Figure 3 is a diagrammatic sectional view of a working cylinder, showing the position of the parts with the intake port open.

Figure 4 is a similar view, showing the exhaust port closed by the piston.

Figure 5 is a similar view, with the exhaust port closed by the sleeve.

Figure 6 is a similar view, with the exhaust port open.

The invention has relation to internal combustion engines, having for an object the provision of an improved two-cycle engine wherein the charge will be fully pre-compressed before delivery to the working cylinders, and wherein a minimum number of working parts are employed and a high degree of efficiency is obtained. Other objects and advantages will hereinafter appear.

The invention consists in the novel construction and combinations of parts, as set forth in the appended claims.

In the accompanying drawings, illustrating the invention, the numerals 1, 1, designate the working cylinders, provided with pistons 2 having the usual driving connection with crank shaft 3. Adjacent to each working cylinder and preferably common to a plurality thereof is a compression cylinder 4, provided with a piston 5 driven from shaft 3 by suitable means, as for instance the crank shaft 6, having two-to-one gearing 7 with said main crank shaft. Intake ports 8 connect the compression and work cylinders, the latter being provided with sleeve valves 9 having corresponding ports 10, and ports 11 of the sleeves cooperating with the exhaust ports 12. The sleeve valves are operated preferably by cams 13, mounted upon crank shaft 3. The compression cylinder 4 is provided with a supply port 14, communicating with the carburetor 15 and controlled by a sleeve valve 16, a check valve or other suitable device.

The operation of the engine is as follows:

Upon the suction stroke thereof piston 5 will draw a charge of fuel through port 14 into cylinder 4, and valve 16 thereupon closing, the compression stroke of the piston will place the charge in cylinder 4 under a high degree of compression. The follower 17 of one of the cams 13 will now rise upon the high point 18 of the cam, raising the related sleeve 9 and thereby bringing ports 8 and 10 into registration and establishing the intake to cylinder 1. The crank arm of piston 2 has at this time advanced approximately 275° from upper dead center, approximately 10° behind the crank arm of piston 5, so that sufficient time is allowed for the completion of the intake and the closing of port 8 before the firing position of the piston 2 is reached. The closing of port 8 by the follower 17 dropping to the dwell 19 of cam 13 will bring ports 11 and 12 into registration, but during the first quarter rotation of its crank arm piston 2 will cover these exhaust ports, at the completion of which movement follower 17 will drop to the low point 20 of the cam, bringing the ports 11 and 12 out of register. As the crank arm of piston 2 reaches a point approximately 70° below upper dead center, follower 17 will rise to the dwell 21 of cam 13, bringing ports 11 and 12 into registration and establishing the exhaust, which will continue until the rise of the follower to the high point 18, when the exhaust port will be closed and the intake again opened.

While the piston 2 of one cylinder is upon the firing stroke, piston 5 will again draw in and compress a charge of fuel, which will be delivered to the opposite working cylinder, the two cylinders, having piston crank arms set 180° apart, being thus charged alternately.

Owing to the rapidity of action of the compression piston 5, it is desirable that the fuel be delivered to cylinder 4 under super-atmospheric pressure, in order to insure rapid and complete charging of said cylinder, to equalize the resistance and to secure a maximum effectiveness of carburetion.

For this purpose a low compression chamber 22 is inserted between port 14 and carburetor 15, said chamber being provided with a suitable pump 23, shown as a rotary pump geared at 24 to the crank shaft 3.

The grouping of compression and working cylinders shown is subject to extensive modification without departure from the

spirit of the present invention, according to which any number of either such cylinders may be employed, variously related to each other and to the crank shaft.

5. The engine, being compact, light of weight, simple in operation, well balanced, and capable of developing a high degree of power, is adapted for use as a vehicle, airplane, marine or stationary engine.

10. I claim:

1. In an internal combustion engine, a plurality of working cylinders, pistons therein, and means for supplying charges of fuel to said cylinders, including a compression cylinder and a piston therein adapted both to draw in a charge of fuel and to fully pre-compress the same while one of the working pistons is upon its explosion stroke.

2. In an internal combustion engine, two working cylinders, pistons therein, a crank shaft connected to said pistons, a compression cylinder located between said working cylinders, a piston therein, and an auxiliary crank shaft connected to said last-named piston, the auxiliary shaft mounted in bearings and lying wholly between the working pistons.

3. In an internal combustion engine, two working cylinders, pistons therein, a crank shaft connected to said pistons, a compression cylinder located between said working cylinders, a piston therein, and an auxiliary crank shaft connected to said last-named piston, said cylinders and shafts having their axes lying in a common plane.

35. 4. In an internal combustion engine, a

working cylinder, a piston therein, a compression cylinder, a piston therein, an intake port connecting said cylinders, an exhaust port in the working cylinder, a sleeve in the working cylinder having intake and exhaust ports, and operating means for said sleeve adapted to hold said intake ports normally out of registration and said exhaust ports normally in registration, to bring the intake ports into registration during a given portion of the cycle and to move the exhaust ports out of registration during the diametrically opposite portion of the cycle.

5. In an internal combustion engine, two working cylinders, pistons therein, and means for supplying a charge of fuel alternately to said cylinders, including a compression cylinder, a piston therein, a two-to-one ratio driving connection between the compression and working pistons, and means for supplying fuel at super-atmospheric pressure to said compression cylinder.

6. In an internal combustion engine, two working cylinders, pistons therein, and means for supplying a charge of fuel alternately to said cylinders, including a compression cylinder, a piston therein, a two-to-one ratio driving connection between the compression and working pistons, and rotary pump means for supplying fuel to said compression cylinder.

In testimony whereof I affix my signature.

RALPH F. CRAWFORD.
